UNITED STATES PATENT OFFICE.

PAUL H. TAYLOR, OF WAKEFIELD, MASSACHUSETTS; GEORGE M. POLAND ADMINISTRATOR OF SAID PAUL H. TAYLOR, DECEASED.

PIANO.

Application filed May 23, 1925. Serial No. 32,434.

This invention relates to pianos and particularly to the type known as grand piano, and aims to provide both an improved piano string plate and case therefor, having, among 5 others, the novel features and advantages hereinafter pointed out.

In the drawings of the embodiment of my invention selected for illustration and description herein,

10 Fig. 1 is a plan of the string plate and also of the case with the top removed to show the case in outline;

Fig. 2, a side elevation of the case from the left, Fig. 1;

15 Fig. 3, a side elevation from the right, Fig. 1, the molding and legs being shown in conventional form in each instance; and,

Fig. 4 is a vertical cross-section of the plate along the line 4—4, Fig. 6, passing through 20 the index numerals 8 and 11^a;

Fig. 5 is a vertical cross-section lengthwise of the plate on the line 5—5, Fig. 1, and passing through the numeral 13; and

25 Fig. 6 is a partial plan of the plate and its strings showing the hammer line and hammers, the dampers being omitted for clearness and the plate being broken away each side of the hammer line.

Referring to Fig. 1 of the drawings, the 30 string plate 1 there shown has the usual straight front edge 2, its right hand or treble edge 3 being straight or nearly straight and at approximately a right angle to the front edge throughout a portion of its length, and 35 slightly convex throughout the remainder of its length, as distinguished from the conventional plate which is concavo-convex in outline at its treble or right hand edge.

At its rear end the treble side edge 3 of the 40 plate curves sharply rearwardly around toward the bass side of the plate to form the rear end or lobe 4 which is unsymmetrical or at one side of the plate, and in turn blends into a concavo-convex side edge 5 sloping at 45 the bass side over toward the latter edge, terminating in a short length of straight edge leading to the front edge 2 and meeting the same at substantially right angles thereto.

The plate 1 is provided with the usual 50 front pin block shelf 6, a treble side web 7 extending to and partially around the rear end and expanding into a wider web 8 on the bass side, said web at various points being pro-

vided with openings 9 to lighten the construction, reduce the area to be finished and to increase to a maximum the area of unrestricted contact between the sounding board and the air.

Extending in a broad sweep from near the rear end of the string plate, at the bass side 55 of the lobe 4, forwardly and toward the treble side, is a curved rib 10, supported along its concave side by the web 11, which, in turn, is connected by the stress receiving web members 11^a and 11^b with the curved margin 60 of the lobe 4, whereby is formed a truss construction, so to speak, resulting in an unusually sturdy structure capable of withstanding the stresses imposed upon it by the tensioning of the strings and requiring less reinforcement by ribs than under present practice. The curved rib 10 is further supported by the longitudinal ribs 12, 13 which extend from the front edge of the string plate rearward to the back edge of the lobe 4, intersecting and supporting the rib 10 where they 65 cross. The longitudinal rib 13 is shown extended in a direction generally at right angles to the front edge of the string plate, while the rib 12 is shown extended from the front 70 edge of said string plate diagonally rearward toward the treble side of the plate and terminated in and at the back edge of the lobe 4. As compared with the conventional string 75 plate which requires four substantially longitudinal strengthening ribs, my improved truss structure described, enables me to obtain the required strength by the use of fewer ribs.

My improved string plate is provided with the usual tuning pins 16, a part only of which 80 are designated by the reference numerals in the front pin block web 6, said string plate being also provided in the lobe 4 with the bass or lower scale hitch pins 17 on the raised step 18, and with the treble or upper 85 scale hitch pins 19 on the web 11. The base bridge 20, and the treble bridge 21, rise from the sounding board 25 beneath the string plate and protrude through said string plate. Between the tuning pins 16 and the hitch pins 17 are secured the strings 22 of the bass scale, broken out for clearness, and between said 90 tuning pins and the hitch pins 19 are secured the strings 23 of the treble scale, a portion 95 of them also being shown broken out to promote clearness. It will be noted that the 100 105

treble bridge 21 is substantially a continuous sweep or curve in outline and thus is much easier and less expensive to construct than if of concavo-convex outline like the treble bridges in common use.

It is a well known fact that the large size pianos possess certain inherent qualities of tone due to the longer lengths of strings which are employed for the lower notes. It 10 is a most important point in the design of a small piano to attain as nearly as possible this desirable tone quality in spite of the limited conditions imposed by the reduced size. For this reason attention is given to 15 the placing of the string, or strings, which compose the lower notes, in order that they may have as great a vibrating length as the design will admit.

It is well known that the lower the note, 20 the longer must be the string of a given unit weight to produce the correct pitch. It is also well known to those skilled in the art that to obtain the correct pitch, with satisfactory tone quality, in the lower or bass 25 scale, single strings, if used, would require to be of such extreme length as would be prohibitive within the limits of the ordinary piano plate. Accordingly resort is customarily had to the expedient of winding said 30 bass strings with one or more covering wires, the winding being the best known substitute for increased length of the strings. The added weight of the winding or covering wires makes up, in some degree, for the shortened length of the core string.

The practice of winding or covering the strings tends greatly to detract from the true tone quality of the strings, and the covering wires take up so much additional room that 40 it is difficult to place them within the necessarily limited available space, especially in the case of small grand pianos which, at present, are by far the most popular sizes.

It becomes extremely desirable, therefore, 45 to increase the lengths of the lower bass strings to such an extent as will obviate the necessity, in part, at least, for the heavy winding of such strings.

To that end I have conceived the novel 50 plan of reversing the outline of the conventional string plate, to throw the lobe from the left or bass side to the right or treble side making the treble side edge straight, or nearly so, and preferably somewhat convex to- 55 ward the rear end, while the bass side is more or less concave as preferred, much as the treble side edge has heretofore commonly been made. By so doing, the treble side of the rear end of the plate will be the longer, 60 which permits the entire bass scale to be ex- 65 tended diagonally to the right and across the treble scale, into the area of the lobe 4 at the treble side of the instrument and so obtain a greatly increased length of the bass scale wires without increasing the length of the

plate. From my present tests, I have found that the best results are obtained if the diagonal lines of the bass strings are approximately at or below an angle of 60° to the hammer line. This results in a greatly increased string length between the usual agraffes 24 and bridge 20 which is extremely desirable and produces an increased volume of tone and of superior quality for a string of given weight or character.

In the drawings, Fig. 1, I have shown the strings 22, as representative of the bass scale, and one will readily observe the increased length of these strings, as compared with the corresponding strings on the conventional plate, of the same scale. Upon my novel plate of given measurement for the small size grand piano, I obtain an increase in length of the lower bass strings of about ten inches over the corresponding strings on a conventional 85 plate. In other words, I obtain on my novel plate in what is ordinarily termed a baby grand piano, a length of string that can now be used only in a much larger grand piano.

In my novel plate, it is possible, see Fig. 1, 90 to position the bass or overstrung scale at a greater angle to the treble or understrung scale than is possible in the conventional plate, thus more evenly distributing the strain over the convex rear end or lobe 4 of the 95 plate with less strain on certain portions. I also prefer to string the treble scale somewhat diagonally to the rear and right, i. e., in the same general direction as the bass scale, but at a greatly reduced angle, as shown.

It is also well known that the larger the area of sounding board made available for use and not covered by the plate, the greater is the active acoustic effect, and it will be noted that when using my improved plate, 105 the uncovered area of the usual sounding board 25 below it, and corresponding generally to it in outline and size, is much larger than is the area of the usual sounding board in use with the conventional form of plate.

It is also recognized that the nearer to the center of the free vibrating portion of the sounding board the acoustic bridges are positioned, the greater and more satisfactory will be both the vibration of the board and the volume of sound given out thereby, and the purer the quality of tone, and it will be noted that in my improved construction, the treble or upper scale bridge 21 is more nearly positioned at the approximate center of the 115 sounding board 25 than is possible in connection with the conventional board.

The hammer line 26 of the scales herein shown as a right line must, for the best results, be in a given position relative to the 120 length of vibrant section of the scale and relative to the tuning pins to which the ends of the wires are attached.

As the length of string is increased, the distance of the hammer line would ordinarily 125

be moved inward away from the plate edge. But the farther inward the hammer line is moved, the longer must be the keys and, therefore, the heavier and slower the action.

5 Hence the desirability of keeping the hammer line as near as practicable to the front of the plate.

By stringing the bass scale at a pronounced angle toward the rear treble side of the instrument, it becomes possible to retain the desired length of string between the tuning pins and the hammer line and at the same time retain the hammer line close enough to the front plate edge to keep the length of the 15 keys within desirable limits.

Heretofore grand and concert grand size pianos necessarily had long keys, while the small or baby grand sizes were supplied with the short keys for no other reason than that 20 it was not necessary to use long ones. The improved piano plate described herein offers a satisfactory solution of what has heretofore been a serious difficulty. It is now possible by the use of my invention to use a short 25 key 27^a for the lowest bass note as well as the others, thereby obtaining a common hammer line, and still obtain string lengths corresponding to the grand and concert grand size.

30 It is also a well established principle of construction that to obtain the best results, Fig. 5, one of the two felts of the damper 27^b, or a portion of the one felt if one only is used, should strike the string over the point 35 where the hammer 27^c strikes, and the other felt, or other portion of the felt, should strike the string in the rear of the spot where the hammer strikes in order that proper damping of the vibrations may be effected. Such a 40 damper may be termed a full-fashioned or full size damper. In the conventional string plate supported by four ribs, the ribs take up so much room that, in connection with the acute angularity of the ribs, there is not left 45 sufficient room to use, in all cases, full size or full-fashioned dampers at the hammer line, those dampers adjacent the ribs being necessarily both shorter than usual and pushed forward of the hammer line so that, 50 in some cases, the damper will not damp the string as it should. It will be noticed, Fig. 1, that by my improved construction, I am able to use full size dampers 27^b on all strings, each damper damping the string at the hammer line, and also in the rear thereof.

55 In the conventional plate in connection with the higher tone and shorter strings, the construction is so crowded that it has hitherto been impossible to use agraffes for supporting these high pitch strings and it has been the practice to resort to the use of what is known as the inverted V-bar near the right hand end of the treble scale, below and against which the high pitch strings, have 60 been stretched to take the places of the

agraffes which were omitted. This V-bar is a heavy and objectionable feature of construction and in my improved construction, I am able to do away with this bar entirely and use agraffes or other devices throughout as 70 indicated, these agraffes still leaving room for the hammers and dampers to function correctly. Furthermore, the additional room obtained between the bass strings on my novel plate, by virtue of the fact that windings for 75 some of these strings in some cases are unnecessary, permits a reduction in the separation of the strings 22 constituting a unison, and thus makes possible the use of a narrower hammer. 80

Another advantageous feature is the reduction in the loading or weight of winding of the strings with consequent reduction in the amount of tension required to bring the string or unison up to pitch. This reduction 85 in required tension results in a decrease of stress applied to the agraffes, tuning pins and pin blocks.

It will be noted that in its general shape my novel plate, as here shown, corresponds 90 very closely to the figure of a right triangle. If the front edge of the plate be considered the base of the right triangle and the treble side of the plate as the perpendicular thereto, which it substantially is and should be, except in so far as it is only slightly modified for reasons of appearance of the exterior, then it will be found that in my plate the direction of the longest bass string is substantially identical in direction, if not in length, with the 100 direction of the hypotenuse of the above described right triangle; and, therefore, the base string which lies in the direction of the hypotenuse must be the longest string which can be strung on a given length of piano 105 plate.

Or if a right triangle be erected on the hammer line as a base, with a perpendicular equal to the greatest distance between the hammer line and rear end of the plate, then the hypotenuse will substantially coincide with the 110 longest base string.

Further if a right triangle be erected forward of the hammer line with a line corresponding to the lowest base string projected 115 for a hypotenuse, and the hammer line extended to the left as a base, then the perpendicular from the base intercepting the hypotenuse will coincide with the key lengths, as the shortest distance between the two 120 points.

The right hand or treble side 27 of my improved piano case is, as already stated, slightly curved through a portion of its length. This is an advantage in that a curved surface 125 does not show the blemishes or imperfections in the finish of the wood as distinctly as does a straight or flat surface of the same length. Consequently less time and labor is required to finish the curved surface and any 130

remaining imperfections will be less noticeable. The left hand or base side 28, as shown, is partly concavo-convex in outline forming with the treble side a lobe 29 between them and with a straight section 30 extended to the straight edge 31, conforming generally to the shape of the plate.

My invention is not restricted to the particular embodiment thereof illustrated herein.

10. Claims:

1. In a piano provided with a usual keyboard, the combination with a string plate of unsymmetrical outline presenting a back lobe in the rear of the treble scale side of the instrument, of a treble scale of wires opposite the treble keys, and a bass scale of wires having its front end adjacent the bass keys and extended at a pronounced diagonal direction across the treble wire scale and having its back end in said lobe, whereby a greater length of bass strings is obtained in a piano of given depth from front to back with corresponding increase of bass volume.

2. In a piano having a usual keyboard, the combination with a string plate of unsymmetrical outline presenting a back lobe in the rear of the treble side of the instrument of a treble scale of wires opposite the treble keys and extended rearward and slightly diagonally toward the treble side of the instrument, and a bass scale having its front end adjacent the bass keys and extended in a markedly diagonal direction across the treble scale to bring its rear end within said lobe, whereby a greater length of bass strings is obtained in a piano of given depth with corresponding increase of bass volume, and a hammer line which is a right line for both scales provided at a substantially uniform distance from the front ends of the keys.

3. In a piano, the combination with a suitable keyboard and string plate, of strings secured to said plate, hammers for said strings with a right hammer line, and bass strings extended in a markedly diagonal direction from the keyboard, whereby to gain increased length of strings between the usual front points of attachment and the hammer line, and position the latter at a minimum and uniform distance from said keyboard for both scales.

4. A piano plate having a lobe at the treble scale side, a treble scale and a bass scale for said plate, a bass scale bridge on the treble scale side of a longitudinal line through the plate midway between its two side edges, and keys for said scales having a right hammer line.

5. A piano plate having bass scale strings and treble scale strings having a right hammer line, and full-fashioned dampers striking the strings at the hammer line and in the rear thereof.

6. A piano plate having a substantially

straight front edge, a partially convex treble side edge, a concavo-convex bass side edge, and a lobe formed by and between said edges at the rear of the plate and a bass scale of wires of unusual length on the plate and extended angularly across it from the bass edge into the lobe.

7. A piano plate having a substantially straight front edge, a slightly convex edge, a concavo-convex edge, all so related that if a right angle triangle were erected with its base on the hammer line and with the perpendicular of the triangle coinciding with the treble edge of the plate, the hypotenuse of the triangle would be substantially adjacent to the concavo-convex edge of the plate, and bass and treble scales of wires on the plate so arranged as to permit the use of a right hammer line and white keys of substantially equal length.

8. A piano plate having a treble side edge comprising a straight section blending into a convex curved section and a concavo-convex bass side edge, said edges forming between them a lobe at the rear treble side corner of the plate and a bass scale with an extra long bass string from the bass end of the front plate edge diagonally across to the lobe, and a treble and bass scale having a right hammer line.

9. A piano plate having a treble scale, and a bass scale, both having a right hammer line, the lowest string of the bass scale being so positioned on the plate that it will substantially coincide with the hypotenuse of a right triangle whose base is the hammer line and whose perpendicular is the longest distance between the hammer line and the rear end of the plate.

10. A piano plate having a treble scale, and a bass scale, both having a right hammer line, the lowest string of the bass scale being so positioned on the plate that it will substantially coincide with the hypotenuse of a right triangle whose base is the hammer line and whose perpendicular is a line drawn from the hammer line to the hitch pin of the lowest bass string.

11. A piano case having a substantially straight front edge, a partially convex treble side edge blending directly into a straight side edge, a concavo-convex bass side edge, and a lobe formed by and between said edges at the rear of the case in combination with a plate of a similar outline having a bass scale extended from the bass side edge into the lobe, and a treble scale, both of which permit the use of a right hammer line.

12. A piano case having a substantially straight front edge, a slightly convex edge, a concavo-convex edge, all so related that if a right angle triangle were inscribed within the margins of the case with its base on the hammer line and with the perpendicular of

the triangle adjacent the treble edge of the case, the hypotenuse of the triangle would be substantially adjacent to the concavo-convex edge of the case.

- 5 13. A piano plate having bass and treble scales thereon with a right hammer line, the lowest bass string located substantially in the position of the hypotenuse of a right angle triangle, with respect to the front and treble 10 side edges of the plate, by virtue of which location, the lowest bass string is the longest string which can be placed on a plate of any given length and width, and a treble scale having a right hammer line with the bass 15 scale.
14. A piano plate having the straight front edge 31, convex treble edge 26, concavo-convex bass edge 28, the lobe 29 between said convex and concavo-convex edges with a bass

scale 22 thereon, the lowest string of which 20 owing to the shape of the plate is of unusual length relative to the plate and extends to the rear end of the plate.

15. A piano plate having the straight front edge 31, convex treble edge 26, concavo-convex bass edge 28, the lobe 29 between said convex and concavo-convex edges with the bass 25 scale 22, treble scale 23 and white keys of uniform length.

16. A piano plate having a bass scale of 30 strings and a treble scale of strings with full-fashioned dampers striking the strings at a common hammer line for both scales, and white keys of uniform length for the scales.

In testimony whereof, I have signed my 35 name to this specification.

PAUL H. TAYLOR.

CERTIFICATE OF CORRECTION.

Patent No. 1,709,045.

Granted April 16, 1929, to

PAUL H. TAYLOR.

It is hereby certified that error appears in the printed specification of the above numbered patent requiring correction as follows: Page 5, line 4, claim 12, after the word "case" and before the period insert "in combination with a plate of a similar outline having a bass scale extended into the lobe, and a treble scale, both of which have a right hammer line"; and that the said Letters Patent should be read with this correction therein that the same may conform to the record of the case in the Patent Office.

Signed and sealed this 21st day of May, A. D. 1929.

(Seal)

M. J. Moore,
Acting Commissioner of Patents.
